UNITED STATES PATENT OFFICE.

WALTER T. GORTON, OF THE UNITED STATES ARMY, SPRINGFIELD, MASSACHUSETTS

MACHINE GUN.

Application filed July 12, 1922. Serial No. 574,558.

(GRANTED UNDER THE ACT OF MARCH 3, 1883; 22 STAT. L. 625.)

The subject of this invention is a machine gun designed primarily for use on aircraft. The gun is intended for use as a fixed synchronized weapon and embodies features of construction which experience has shown to be desirable and which can be obtained only with great difficulty, if at all, in guns of the usual ground type converted for aircraft use. Guns of this class are usually mounted in pairs side by side and since the space available for them and their ammunition boxes, synchronizing gears, and mounts is of necessity extremely limited, a symmetrical arrangement of all this equipment is very useful. In order to obtain this symmetrical arrangement special provision must be made in certain features of the gun, principally in the means for feeding, ejection of empty cartridge cases and the empty end of the cartridge belt, (which may be of either fabric or disintegrating metallic link construction) attachment and operation of the trigger motor and an arrangement of the handle by which manual operation of the mechanism of a gun for loading and unloading and correction of stoppages is effected. Guns of this class are belt fed, the belt entering one side of the gun above the breech of the barrel and being ejected from the opposite side. In order to secure the object sought, provision for entry of the belt from either side is essential. The trigger motor is mounted upon the side and correspondingly, means for mounting it on either side are provided. The empty cartridge cases are ejected from the bottom. The operating handle is located centrally with respect to the width of the gun extending to the rear and downward from the cover, over which it extends as a slide to operate the bolt. With these and other objects in view my invention resides in the novel arrangement and combination of parts and in the details of construction hereinafter described and claimed, it being understood that changes in the precise embodiment of the invention herein disclosed may be made within the scope of what is claimed without departing from the spirit of the invention.

One practical embodiment of the invention is illustrated in the accompanying drawings, wherein:

Fig. 1 is a fragmentary view in longi-

tudinal section of a gun constructed in accordance with the invention; 55

Fig. 1^A is a similar view of the muzzle and muzzle gland;

Fig. 2 is a plan view of a receiver partly in section on the line 2—2 of Fig. 1.

Fig. 3 is a plan view of the receiver with 60 the cover removed.

Fig. 4 is a section on the line 4—4 of Fig. 1.

Fig. 5 is a plan view of the gun, the barrel and jacket removed. 65

Referring to the drawings by numerals of reference:

The receiver is an elongated rectilinear box consisting of side plates 10 and bottom plate 11 suitably joined together as by riveting. The plates have grooves cut in their inner faces adjacent their rear ends for the reception of tongues formed on the rear plate 12, which plate is assembled with the receiver by sliding it into place from above, 70 and is held in place by suitable means such as the catch 13 which hooks under the rear edge of the bottom plate. The forward end of the receiver is closed by a trunnion block 14 which may be conveniently riveted in 80 place. The trunnion block is bored for the reception of the breech end of the barrel 15 with a close sliding fit and also counterbored and tapped for threaded engagement with the rear end of the barrel jacket 16 as seen 85 most clearly in Fig. 1.

Connected to the breech end of the barrel 15, preferably by screwthreads 17 is a barrel extension 18 which extends rearwardly and terminates adjacent the buffer 12'. The 90 rear portion of the barrel extension rests upon a lock frame 19 which is positioned in the receiver and is adapted for the reception of the accelerator and breech bolt lock.

The accelerator mechanism may comprise 95 an accelerator pin 20 working in a guide 21 carried in the lock frame and urged forwardly by suitable means such as the coiled spring 22, which is confined between the guide and the head of the pin. The head of 100 the pin abuts against the rear face of a depending portion 23 of the barrel extension which portion is slotted as at 24 to receive the accelerator 25 which is pivotally mounted in the lock frame. The extension 18 105 is also slotted at 26 for the reception of

a vertically sliding breech lock 27 which its forward position and primes the cartridge. For the purpose of properly operating the breech lock, grooves 28 are formed on the forwardly projecting ends of the lock frame sides down which the breech lock pin slides upon recoil to unlock the breech bolt, and surface 29 engages the lower face of the breech lock on counter-recoil to force the lock upwardly to engage the breech bolt to lock the same in breech closing position.

Upon recoil the accelerator is acted upon by the cross bar 31 and swung upon its pivot into engagement with the rear cross bar of the depending portion 23 and, upon counter-recoil the impulse of the expanding spring 22 forces the accelerator again into contact with the cross bar 31 urging the same and the barrel extension forwardly.

The breech bolt 32 is mounted for reciprocation between the side bars of the barrel extension and has a longitudinal tongue or rib 25 formed on each side to engage in a slot 33 formed in the inner face of each side bar.

A slot 34 is cut in the lower surface of the breech bolt in position to receive the breech lock 27 when the breech bolt is in its forward position. Upon the bolt at its rear end is an upwardly projecting portion 35 slotted to receive the pivotally mounted sear 36 in the form of a bell crank lever one end of which is adapted to engage in a notch 37 cut in the upper surface of the firing pin 38 and the other arm of which is formed with a V-shape front face extending into a complementary notch formed in the rear edge of slide 39 which slide extends across the portion 35 and slides in a groove formed therein, the ends of the slide positioned adjacent the side plates of the receiver so as to be operated upon by a trigger motor mounted on either side plate.

When the sear slide is forced either to the right or the left the V face on the sear rides along the inclined face of the recess in the slide rocking the sear on its pivot and releasing the firing pin.

The firing pin 38 is mounted for sliding movement in the bolt which is bored longitudinally for its reception. The firing pin may be hollow and urged forwardly by resilient means such as the coiled spring 40 which is herein shown as housed within the pin and confined between a forward abutment, specifically a rivet 41 locked in an aperture formed in the pin, and a pin 42 held in apertures formed in the bolt and passing through alining slots formed in the firing pin.

The firing pin is designed with a forwardly projecting pin 43 which extends through an aperture formed in the forward end of the breech bolt when the pin is in

For the purpose of cocking the firing pin and also extracting a cartridge 44 from the cartridge belt 45 an extractor lever 46 is pivotally mounted in a slot formed in the upper surface of the breech bolt at its forward end. The lever is provided with a finger 47 which engages the forward end of the pin and acts upon the pin to force it rearwardly to cocked position as the extractor is rocked upon its pivot to depressed position.

The lever is formed with a curved upper end 48 which contacts the upper surface of the cartridge case near the head thereof during extraction and positioning of the cartridge and also with laterally extending arms 49 (see Fig. 4) formed at either outer extremity with up-standing wings 50 and ends 51 adapted to contact the cam surface about to be described. Pivotally connected to this upper end is a pair of curved jaws 52 adapted to embrace a cartridge shell and prevent the cartridge from falling during the positioning operation.

Pivotally mounted in the breech bolt are spaced apart members 53 (see Fig. 3) each provided with an ordinary resiliently actuated hook extractor adapted to snap over the head of the cartridge as the bolt moves forwardly to breech closing position and into the cannelure of the cartridge to extract the cartridge as the bolt moves rearwardly on recoil.

The member 46 is constrained to perform the operations above described by means of cam surfaces 54, 55 and 56 which are formed on or attached to the side plates of the receiver. The cam 54 is engaged by the up-standing wings 50 and upon recoil of the bolt, slightly depresses the member 46, forcing the cartridge from the extractor into a groove 57 cut in the front face of the bolt and adapted to receive the head of the cartridge. On counter-recoil the ends 51 engage the cam surface 55 further depressing the member 46 and moving the cartridge downwardly in the groove to position to enter the cartridge chamber. Near the end of the counter-recoil the ends 51 encounter cam surfaces 56 which cause elevation of the member 46 to its original position ready to act on the next cartridge extracted from the belt. As will be understood the ribs, defining the side of the grooves 57 engage in the cannelure of the cartridge shell and serve to extract the shell from the cartridge chamber after the cartridge has been fired.

The receiver is closed by a cover 58 formed on its under surface with spaced apart longitudinally extending ribs 59 forming a support and slideway for a casing 60 which houses the recoil spring 61 guided by a guide pin or rod 62 which may be conveniently

secured to the cover as shown. The casing 60 is formed with a depending lug 63 adapted to seat in a groove formed in the upper surface of the breech bolt so that the 5 casing and bolt may travel in unison on recoil and counter recoil. At its forward end the casing may be formed with a T head 64 (see Fig. 2) adapted to enter a T slot 65 formed in the rear end of a cam plate 66 10 which cam plate also slides in the grooves of the ribs 59, the purpose of such connection being to constrain the cam plate to travel with the casing during recoil and counter-recoil.

15 The cam plate may contain cut-out portions 67 for the purpose of reducing weight, and is also formed with a cam slot 68 which is cut entirely through the plate so that by reversing the plate the cam slot is reversed 20 and operates the member controlled thereby in the reverse direction.

The cartridge belt feeding mechanism, which is controlled by the cam plate 66, comprises a slide 69 mounted to reciprocate 25 transversely of the receiver and formed with an upstanding boss or lug 70 which enters the slot 68. A belt feeding pawl 71 is pivotally mounted on the slide 69 and engages the belt and a cartridge on forward movement 30 to feed the belt into the receiver with a step by step motion and rides over the belt and a cartridge on its reverse or rearward movement. To permit of reversal of this movement, which allows the belt to be fed to the 35 gun from either side, the feed pawl and slide are similar with respect to their longitudinal axis so that they may be inserted in the guide-way on the cover from either side. The belt stop dog or pawl 72 with its brackets 73 may be attached to either side plate of the receiver and the front and rear cartridge stops 74 and 75, respectively, may be attached to either side by either screws or pins.

5 For convenience in operating the gun to load, unload and correct stoppages, a slide 76 (see Fig. 5) is provided formed with a grip 77 extending adjacent the rear of the gun and having its forward end engaged 0 over a lug 78 (Fig. 1) rising from the casing 60 and adapted to reciprocate in a slot 79 cut in the top plate. By grasping the grip and drawing the slide completely to the rear the bolt is drawn back to full recoil position. 5 and a cartridge carried with it and positioned to enter the cartridge chamber when the members are allowed to assume normal position under the impulse of the recoil spring. To effect unloading of the chamber 0 of the gun, the handle is grasped and the slide drawn completely to the rear then allowed to move forward until the rear notch 80 in the slide is engaged with the 5 guide 82 and the slide again drawn completely to the rear and allowed to spring

forward. On the first of these rearward movements a cartridge is extracted from the belt and, on the subsequent forward movement is partially inserted in the chamber. However, the rear notch of the slide is so positioned that when engaged by the rear guide the next cartridge in the slot is not gripped by the extractor, consequently, on the second rearward movement of the slide no new cartridge is taken from the belt, and the live round which had been previously partially inserted in the chamber is extracted and ejected, leaving the gun unloaded.

I claim:

1. A machine gun, embodying cartridge feeding mechanism, a reversible cam plate for operating said mechanism either right handed or left handed, a breech bolt, a connection between the breech bolt and cam plate whereby the bolt and plate are operated in unison, a firing pin in the bolt, a combined cartridge extracting and firing pin cocking member mounted in the bolt, a sear mounted in the bolt and engageable with the pin for holding the same in cocked position and a sear tripping slide operable from either the right hand or left hand side of the gun.

2. A machine gun, embodying cartridge feeding mechanism, a reversible cam plate for operating said mechanism either right handed or left handed, a breech bolt, a connection between the breech bolt and cam plate whereby the bolt and plate operate in unison, a firing pin mounted in the bolt, a sear for holding the firing pin in cocked position and a slide for tripping the sear, operable from either the right or left hand side of the gun.

3. A machine gun, embodying cartridge feeding mechanism, a reversible cam plate for operating said mechanism either right handed or left handed, and a breech bolt connected to said cam plate.

4. A machine gun, embodying reversible cartridge feeding mechanism, a breech bolt, means connected to the breech bolt and operable therewith for actuating the feeding mechanism either right handed or left handed, a sear and a trip for the sear operable from either the right hand or left hand side of the gun.

5. A machine gun, embodying a reversible cartridge feeding mechanism, recoil operated means for actuating the feeding mechanism either right handed or left handed and means for manually operating said first mentioned means.

6. A machine gun, embodying a reversible cartridge feeding mechanism, means for actuating the feeding mechanism either right handed or left handed and means for manually operating said first mentioned means.

7. A machine gun, embodying a reversible cartridge feeding mechanism and means for actuating said mechanism either right handed or left handed.
8. A machine gun, embodying a reversible cartridge feeding mechanism, and reversible means for actuating said mechanism either right handed or left handed.
9. In a machine gun, the combination of a breech casing having a transverse cartridge feeding channel and mechanism for automatically feeding cartridges into said channel from left to right, or vice versa, said mechanism comprising a reciprocating member carrying means adapted to be reversed when it is desired to change the direction of feed.
10. In a machine gun, the combination of a breech casing having a transverse cartridge feeding channel and mechanism for, at will, feeding cartridges into said channel from left to right, or vice versa, said mechanism comprising a reciprocating member carrying a reversible cam plate.
11. In a machine gun, the combination of a breech casing having a transverse cartridge feeding channel, with means for, at will, feeding cartridges into said channel from left to right, or vice versa, said means comprising a reversible feed slide carrying a feed pawl, and a reciprocating member for actuating said slide automatically.
12. In a machine gun, the combination of a breech casing having a transverse cartridge feeding channel and mechanism for, at will, feeding cartridges into said channel from left to right, or vice versa, said mechanism comprising a reciprocating member carrying a flat plate adapted to be reversed when it is desired to change the direction of feed and having a cam slot opening into each face thereof.
13. In a machine gun, the combination of a breech casing having a transverse cartridge feeding channel, reversible mechanism for feeding cartridges into said channel, means to actuate said mechanism for feeding said cartridges from left to right, or vice versa, and a feed extractor adapted to cooperate with said means regardless of the direction it feeds.
14. In a machine gun, the combination of a breech casing having a transverse cartridge feeding channel, and means for automatically feeding a cartridge belt into said channel from left to right, or vice versa, as desired, said means comprising a reversible feed slide and a feed pawl carried thereby, a stop pawl for preventing retrograde movement of said cartridge belt, and cartridge stops for preventing over-feeding movement of said cartridge belt and for insuring proper alignment of the cartridges with the central vertical plane of the gun, said stop pawl and the cartridge stops being arranged, respectively, on opposite sides of the gun and so constructed and mounted as to permit their transfer to the opposite sides of the gun, respectively, when the feed slide is reversed, thereby adapting said parts for co-operation with said slide for either direction of feed.
15. In an automatic gun the combination of a breech casing having a transverse cartridge feeding channel, a mechanism for at will feeding cartridges into said channel from left to right, or vice versa, and an extractor operable irrespective of the direction of feed.
16. In a machine gun, the combination of a breech casing having a transverse cartridge feeding channel, a mechanism for at will feeding cartridges into said channel from left to right or vice versa, and means for actuating said mechanism irrespective of the direction of feed.
17. In a machine gun, the combination of a breech casing having a transverse cartridge feeding channel, and mechanism depending on its position for feeding cartridges into said channel from left to right or vice versa.
18. In a machine gun, the combination of a breech casing having a transverse cartridge feeding channel and a mechanism for feeding cartridges into said channel from left to right or vice versa.

WALTER T. GORTON.
